UNITED STATES PATENT OFFICE.

EVERETT HARLOW BIXBY, OF ASTORIA, OREGON.

EXTENSION GRIP FOR ELECTRIC-LAMP CONNECTERS.

Application filed May 1, 1926. Serial No. 106,032.

My invention relates to an extension grip for electric lamp connecters.

The object of my invention is to provide an extension grip of simple and inexpensive construction, adapted to be easily and quickly clamped onto any standard electric lamp connection, and further adapted to accommodate variations in the size of the connection.

Further to provide the extension grip with a shank of substantial length adapted to be placed over the cord of the electric connection, so as to provide an ample hand-hold and insure that when the connecter is pulled out of its socket the pull will not be applied to the cord.

And further to provide said extension grip with finger-holds providing a means whereby the extension will not turn or slip in the hand.

And furthermore to provide an extension grip adapted to be attached to a standard electric lamp connection without changing or substituting any part of the said connection.

I attain my object by means of an electric-
25 connecter holder comprising a tubular longitudinally divided two part shank, the edges of the parts bearing on each other, the shank parts formed at one end with clamping head portions, said shank parts are provided with external laterally inter-locking lugs at their abutting edges, said lugs being adapted to hinge said parts one in the other, thereby to permit the spreading apart of the clamping head ends of the shank for the receiving of connecters of various sizes, said inter-locking lugs serving also to provide finger holds and means for fastening the shank parts together, and furthermore a split bushing of resilient material is secured within the hollow of the shank for encompassing the cord of the connecter secured in the said clamp-head portions.

The further details of construction of my invention, and the mode of its use is illustrated in the accompanying drawing, and hereinafter described:

In the drawings:

Figs. 1 and 2 show the two companion halves of which my extension grip is composed and illustrate the provision on each half of inter-locking lugs;

Fig. 3 shows a side elevation of two parts of my extension grip assembled on an electric connecter and bolted together;

Fig. 4 shows a side elevation similar to that shown by Fig. 3 and the parts cut away

to show the means provided for gripping the connecter, the view seen in Fig. 4 being at right angles to that seen in Fig. 3;

Fig. 5 shows an electric fixture and illustrates the mode in which my invention is used in practice;

Fig. 6 shows the means employed, namely a protective split-bushing, for the electric cord of the electric connecter.

My invention is stamped out of metal, and consists of two parts *a* and *b* preferably with flared ends *h*, and exactly alike except for the lugs *c* with the seating cavities on one and the lateral arms *d* on the other which when assembled lock one in the other.

The clamping-head *e* is composed of the parts *a'* and *b'*, and are flared so as to form a bell-shaped opening with a convex rim *f* adapted to hold any standard electric connecter as *g*. The bolt *h* in the holes *h'* is provided to hold the two parts together and the shanks *a²* and *b²* form the tubular-like handle *i* through which the electric cord *j* extends and is spread at the end *k* so as to provide a degree of adjustment to the size of the connecter. As the strain from the bolt *h* is centered on the interlocked lugs it serves to lock them in place. A resilient split-bushing *l* (Fig. 6) that may be slipped in place over the cord is provided as a guard against wear on the insulation and as a grip to hold the cord against a sudden pull or jerk.

My invention is useful in many ways as for instance when attaching the connecter inside a lamp shade *n*, as in Fig. 5 which also shows how the lugs *c* and *d* serve as finger holds as at *m*. It may be used as a handle for an extension light, and it may be attached on any connecter without removing the cord, it being only necessary to assemble the extension grip around the connecter and cord and bolt it in place.

I claim:

1. An electric-connecter grip comprising, a tubular longitudinally divided two-part shank, the edges of the parts bearing on each other, the shank parts formed at one end with clamping-head portions and provided at the other end with external means for locking the shank-parts together, said means being adapted to hinge said parts one on the other, the latter ends of the shank parts being curved outwardly towards the extremities to increase the degree of the said spreading apart, said interlocking lugs serv-

ing also to provide finger-holds, and means for fastening the shank parts together.

2. An electric-connector grip comprising a tubular longitudinally divided two-part shank, the edges of the parts bearing on each other, the shank parts formed at one end with clamping-head portions, and provided at the other end with external laterally interlocking lugs at their abutting edges, said lugs being adapted to hinge said parts one on the other thereby to permit the spreading apart the clamping-head ends of the shank for receiving connectors of various sizes, the latter ends of the shank parts being curved outwardly towards the extremities to increase the degree of the said spreading apart, and means for fastening the shank parts together.

3. An electric-connector grip comprising, a tubular longitudinally divided two-part shank, the edges of the parts bearing on each other, the shank parts formed at one end with clamping-head portions and provided at the other end with external laterally interlocking lugs at their abutting edges, the lugs of one of said parts provided with seating cavities and the lugs of the other part consisting of lateral arms seated in said cavities, and means for fastening the shank parts together.

4. An electric-connector grip comprising a tubular longitudinally divided two-part shank, the edges of the parts bearing on each other, the shank parts formed at one end with clamping-head portions and pro-

vided at the other end with external laterally interlocking lugs at their abutting edges, said lugs being adapted to hinge said parts one on the other thereby to permit the spreading apart the clamping-head ends of the shank for receiving connectors of various sizes, the latter ends of the shank parts being curved outwardly towards the extremities to increase the degree of the said spreading apart, and means for fastening the shank parts together.

5. An electric connector-grip comprising a tubular, longitudinally divided shank, the shank parts formed at one end with complementary clamping-head portions, and provided at the other end with laterally projecting interlocking lugs holding the parts together, and means for fastening the shank parts together.

6. An electric connector-grip comprising a tubular, longitudinally divided shank, the shank parts formed at one end with complementary clamping-head portions, and provided at the other end with laterally projecting interlocking lugs holding the parts together, said interlocking lugs extending a substantial distance beyond the circumference of the shank, thereby to adapt said lugs to serve as finger holds, and means for fastening the shank parts together.

EVERETT H. BIXBY.
